CLAIM

The ornamental design for the torque wrench, as shown and described.

DESCRIPTION

FIG. 1 is a perspective view of a torque wrench in accordance with an embodiment of the present invention; FIG. 2 is a front view of the torque wrench of FIG. 1; FIG. 3 is a rear view of the torque wrench of FIG. 1; FIG. 4 is a left side view of the torque wrench of FIG. 1; FIG. 5 is a right side view of the torque wrench of FIG. 1;

(Continued)

FIG. 6 is a top view of the torque wrench of FIG. 1; and, FIG. 7 is a bottom view of the torque wrench of FIG. 1. The broken lines of the torque wrench in FIGS. 1-7 are illustrative of portions of the torque wrench that form no part of the claimed design.
